GRINDING WHEEL SPINDLE POSITIONING
AND RECIPROCATING MECHANISMLennart A. Kasparsen, Worcester, Mass., assignor
to Norton Company, Worcester, Mass., a corpora-
tion of Massachusetts

Application September 21, 1945, Serial No. 617,801

9 Claims. (Cl. 51—34)

1

This invention relates to grinding machines and more particularly to a grinding wheel spindle positioning and reciprocating mechanism.

One object of the invention is to provide a simple and thoroughly practical mechanism for positioning or reciprocating a grinding wheel spindle axially within its bearings. Another object of the invention is to provide a grinding machine with a spindle positioning and reciprocating mechanism which is arranged so that the spindle may be positioned manually for a shoulder grinding operation, reciprocated continuously for a plunge-cut grinding operation or may be locked positively as desired. Another object of the invention is to provide a spindle locking device and a clutch operated reciprocating mechanism which are interlocked so that the clutch cannot be engaged to start spindle reciprocation while the spindle is positively locked. Another object of the invention is to provide an interlocking mechanism which is arranged to prevent engagement of the locking device to positively lock the spindle when either of the clutches are engaged for power reciprocation or manual positioning of the wheel spindle. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a vertical sectional view, through a grinding wheel slide, showing the improved wheel spindle positioning and reciprocating mechanism partly in section and partly in elevation;

Fig. 2 is a vertical sectional view, on an enlarged scale, taken approximately on the line 2—2 of Fig. 1;

Fig. 3 is a horizontal sectional view, on an enlarged scale, taken approximately on the line 3—3 of Fig. 1;

Fig. 4 is a vertical sectional view, on an enlarged scale, taken approximately on the line 4—4 of Fig. 1;

Fig. 5 is a plan view of the eccentric and connecting rod.

A grinding machine has been illustrated in the drawings comprising a base 10 which supports a transversely movable wheel slide 11 on a V-way 12 and a flat-way 13 on the base 10. The wheel

2

slide 11 supports a rotatable grinding wheel 14 which is mounted on one end of a rotatable wheel spindle 15. The spindle 15 is journaled in suitable bearings 16 and 17 within the wheel slide 11. The right-hand end of the wheel spindle 15 (Fig. 1) is provided with a multiple V-grooved pulley 18 which is connected by multiple V-belts 19 with a suitable source of power such as for example, an electric motor (not shown) mounted on the wheel slide 11.

A wheel feeding mechanism is provided for manually feeding the grinding wheel 14 toward and from the work piece, which comprises a half nut 20 depending from the end side on the wheel slide 11. The half nut 20 meshes with or engages a rotatable cross feed screw 21 which may be rotated by any of the well known wheel feeding mechanisms such as for example, that shown in the expired U. S. Patent to C. H. Norton No. 762,838, dated June 14, 1904. This mechanism has not been illustrated in detail in the present application since it is not considered to be a part of the present invention. Consequently for further details of construction, reference may be had to the above mentioned prior patent.

To facilitate reciprocation of the wheel spindle 15, a flanged sleeve 25 is fixedly mounted on the wheel spindle 15. A worm 26 is keyed to the sleeve 25 and is held in position thereon by collars 27 and 28. A groove 29 is formed between the flanged sleeve 25 and the left-hand end of the worm 26. A collar 30 rides in the groove 29. The collars 27 and 28 may be adjusted to adjust the position of the worm 26 relative to the flange on sleeve 25 so as to vary the width of the groove 29 and thereby take up lost motion between the groove 29 and the collar 30.

To reciprocate the spindle 15 a pivotally mounted yoked arm 31 is provided having a pair of diametrically opposed studs 32 and 33 engaging or mating with diametrically opposed holes formed in the ring 30 (Fig. 2). The yoked member 31 is pivotally supported by a stud 34 which is fixedly mounted in a hole 35 formed in an inwardly extending integrally formed boss extending inwardly from the wheel slide housing. The other end of the yoked arm 31 is connected by means of a stud 36 with one end of a connecting rod 37. The other end of the connecting rod 37 is formed as a strap 38 which surrounds and meets with an eccentric 39 which will be herein-after described.

A suitable driving mechanism is provided for rotating the eccentric 39 so as to transmit an oscillating movement to the yoked arm 31 and

thereby to transmit a reciprocating movement to the wheel spindle 15. This mechanism may comprise a worm gear 40 which is mounted on a vertical shaft 41 journalled in suitable bearings within the wheel slide 11. The worm gear 40 meshes with the worm 26 which is carried by the wheel spindle 15. The upper end of the shaft 41 is provided with a clutch member 42 which is arranged to be engaged by a clutch member 43 mounted on the lower end of a vertical shaft 44. The eccentric 39 is provided with a downwardly extending lug 45 which engages a slot 46 formed in a collar 47 which is pinned to the shaft 44. When the clutch member 43 is moved downwardly into engagement with the clutch member 42, the rotary motion of the wheel spindle 15 will be transmitted to rotate the shaft 44, to rotate the collar 47 and through the groove 46 and the lug 45 to transmit a rotary motion to the eccentric 39. The rotary motion of the eccentric 39 will transmit a reciprocating motion to the connecting rod 37 and thereby to impart an oscillating movement to the yoked member 31 to reciprocate the wheel spindle 15 axially within its bearings. The mechanism above described will serve to transmit a continuous reciprocating movement to the grinding wheel spindle 15 for a plunge-cut grinding operation.

It is desirable in a shoulder grinding operation to provide a manual adjustment for the wheel spindle 15 so that it may be manually moved axially within its bearings to position the side faces of the grinding wheel 14 in the desired relationship with a shoulder or shoulders on a work piece. A manually operable hand wheel 50 is fixedly mounted on the upper end of a shaft 51. The shaft 51 is journalled in bearings 52 and 53 which are fixedly mounted within a housing 54. The housing 54 is fixedly mounted on the upper surface of the wheel slide 11. The near end of the shaft 51 is provided with a bevel gear 55 which meshes with a bevel gear 56. The bevel gear 56 is keyed to a sleeve 57. The lower end of the sleeve 57 is provided with a clutch member 58 which is arranged to engage a clutch member 59. The clutch member 59 is fixedly mounted on a rotatable sleeve 60. The lower end of the sleeve 60 is provided with an integral eccentric 61. The eccentric 61 is arranged to mate with an eccentric aperture 62 (Fig. 5) formed within the eccentric 39. When it is desired to manually position the grinding wheel 14 for a shoulder grinding operation, the clutch member 58 is engaged with the clutch member 59. In this position of the clutch parts, a rotary motion of the hand wheel 50 will be transmitted through the bevel gears 55 and 56 to rotate the sleeve 57, the clutch member 58, the clutch member 59 and the eccentric 61 which will impart a longitudinal movement to the connecting rod 37 and thereby to swing the yoked member 31 precisely to adjust the wheel spindle 15 in an axial direction to position the grinding wheel 14 as desired.

It is desirable to provide means whereby the length of the reciprocating stroke of the wheel spindle 15 may be readily adjusted when desired. An adjusting mechanism is provided whereby the eccentric 61 may be adjusted and locked relative to the eccentric 39 so that the effective throw of the eccentrics may be adjusted. As illustrated in Fig. 5 the eccentrics are set for a maximum reciprocating stroke. By adjusting the eccentric 61 relative to the eccentric 39, the axis of the eccentric 39 may be adjusted toward or from the

axis of the shaft 44. If the eccentric 61 is turned through 180°, the axis of the eccentric 39 will coincide with the axis of the shaft 44 and when rotated will transmit no reciprocatory motion to the wheel spindle.

To facilitate the above mentioned adjustment, a flange or collar 63 is fixedly mounted on the upper end of the sleeve 60. An adjusting knob 64 is slidably keyed on the upper end of the shaft 44. The knob 64 is provided with an index pin 65 which is arranged to engage one of a plurality of index holes 66 formed in the upper surface of the collar 63. A compression spring 67 serves normally to hold the knob 64 in a downward position with the index pin 65 in engagement with one of the index holes 66. When it is desired to adjust the reciprocating stroke, the knob 64 is raised manually to disengage the index pin 65 from index hole 66 and the knob 64 is then rotated to turn the shaft 44 and thus transmit a rotary motion through the collar 47 and the lug 45 to rotarily adjust the eccentric 39 relative to the eccentric 61. After the desired adjustment has been made the knob 64 is released and the compression spring 67 again moves the knob 64 downwardly so that the index pin 65 engages one of the index holes 66 in the collar 63 to lock the two eccentrics in adjusted position.

In order to facilitate precise adjustment of the eccentrics so as to obtain the desired reciprocating stroke, the collar 63 is provided with a graduated scale 68 and the knob 64 is provided with a zero or index pointer whereby the mechanism may be adjusted to obtain a predetermined reciprocating stroke of the spindle 15.

In order to facilitate readily adjusting the mechanism so that the wheel spindle 15 may be locked against endwise movement, or arranged for a manual adjustment for a shoulder grinding operation, or arranged for a reciprocating stroke for a plunge-cut grinding operation, a suitable mechanism is provided for controlling the clutches above described. This mechanism may comprise a pivotally mounted clutch actuating lever 70 which is pivotally supported by a stud 71 which is fixed relative to the housing 54. The right-hand end of the lever 70 (Figs. 2 and 3) is formed as a yoke shaped member having a pair of inwardly projecting diametrically opposed studs 72 and 73 which ride in a groove 74 formed in a spool shaped member 75 which is keyed to rotate with the sleeve 60. The left-hand end of the lever 70 is provided with a latch pin 76 which is normally held in engagement with a plurality of locating holes 77, 78 or 79 formed in the housing 54. A compression spring 80 normally holds the latch pin 76 in engagement with one of the holes 77, 78 or 79. A manually operable knob 81 is provided for manually withdrawing the latch pin 76 against the compression of the spring 80 when it is desired to adjust the position of the lever 70. In the position of the parts as illustrated in Fig. 2, the latch pin 76 is in engagement with the hole 79 so that the sleeve 60 and the shaft 44 are in an upward position with the clutch member 59 in engagement with the clutch member 58. Engagement of the clutch members 59—58 renders the manually operable adjusting mechanism operative so that the wheel spindle may be adjusted axially by means of the hand wheel 50 operative for a shoulder grinding operation.

If it is desired to lock the spindle against endwise movement, the lever 70 is swung to an intermediate position with the latch pin 76 en-

gaging the index hole 78 in which position both of the clutches 42-43 and 58-59 are disengaged.

If it is desired to set the mechanism up for a reciprocatory movement of the wheel spindle for a plunge-cut grinding operation, the control lever 70 is locked into a position so that the latch pin 76 engages index hole 77. This movement causes a downward movement of the shaft 44 and the sleeve 60 so that the clutch member 43 is moved into engagement with clutch member 42. In this position of the parts rotation of the wheel spindle 15 will be transmitted through the mechanism above described to produce a continuous reciprocation of the wheel spindle 15 within its bearings 16 and 17 for a plunge-cut grinding operation, the extent of the reciprocatory movement of the spindle 15 being governed by the relative positions of the eccentrics 38 and 61.

When it is desired to hold the spindle 15 against axial movement, it is desirable to provide a positive locking device whereby the spindle 15 may be locked with a solid end thrust so that it is held positively against endwise movement during a grinding operation. The yoked member 31 (Figs. 2 and 4) is provided with an upwardly extending stud 85 which is formed at its upper end with a frusto-conical end portion 86. A cylindrically-shaped housing 87 is mounted on the upper end of the housing 54 and contains a cylindrical aperture 88 which supports a slidably mounted hollow sleeve 89. The lower end of the sleeve 89 is provided with a frusto-conically shaped aperture 90 which in a downward position mates with the frusto-conical portion 86 of the stud 85. When the sleeve 89 is in a downward position with the frusto-conical aperture 90 engaging a frusto-conical portion 86 of the stud 85, the yoked arm 31 is held against an oscillating motion thereby providing a solid end thrust positively to hold the spindle 15 against axial movement. A compression spring 91 is provided within a central aperture 92 in the sleeve 89. The compression spring 91 is interposed between the bottom of the aperture 92 and a stud 93 which extends through elongated clearance slots 94 in the sleeve 89 and is fixed relative to the housing 87. Elongated slots 94 are provided in the sleeve 89 to facilitate movement of the sleeve 89 relative to the pin 93. It will be readily apparent from the foregoing disclosure that the compression spring 91 normally serves to hold the sleeve 89 in a downward position to lock the frusto-conical aperture 90 in engagement with the frusto-conically shaped portion 86 of the stud 85. A manually operable knob 95 is provided to facilitate raising the sleeve 89 when it is desired to unlock the yoked arm 31 for either a continuous reciprocatory movement of the spindle or a manual adjustment thereof.

It is desirable to provide an interlocking mechanism between the positive locking device and the clutch actuating mechanism so as to prevent engagement of either of the clutches when the spindle is locked against reciprocatory movement. It is similarly desirable to arrange the interlocking mechanism so as to prevent engagement of the locking device when either of the clutches are engaged for power reciprocation or hand adjustment of the wheel spindle. This interlocking mechanism preferably comprises a stud 100 which is slidably mounted within the housing 87. The end of the stud 100 (Fig. 3) is provided with a latch pin 101 which in the position illustrated engages a hole 102 formed in the lever 70, when the lever 70 is in an intermediate position. The stud 100 is normally held with the pin 101 in en-

gagement with the hole 102 by means of a compression spring 103. When the locking device is operative to lock the spindle 15 against reciprocatory movement, that is, when the control lever

- 5 70 is in a central or intermediate position, the pin 100 engaging the hole 102 prevents movement of the control lever 70 to engage either of the clutches since the stud 100 cannot be withdrawn when the sleeve 89 is in a downward position. A 10 manually operable knob 104 is provided for actuating the stud 100. The sleeve 89 is provided with a groove 105 which is formed as a partial cylindrical surface of a diameter slightly greater than the diameter of the stud 100.
- 15 When it is desired to reciprocate the spindle or adjust it manually, the knob 95 is raised to disengage the frusto-conical aperture 90 from the conical surface 86 of the stud 85. When the sleeve 89 reaches its upper-most position, the 20 knob 104 may be moved (Fig. 3) so that the stud 100 slides through the groove 105 in the sleeve 89. During this movement the latch pin 101 withdraws from engagement with the hole 102 thus 25 unlocking the lever 70 so that it may be shifted to engage either of the clutches as desired. When the stud 100 is withdrawn to this position, the 30 stud 100 engaging the groove 105 serves to lock the sleeve 89 in an uppermost position and thereby to prevent engagement of the locking device when either of the clutches are engaged for a 35 continuous reciprocation of the spindle 15 during a plunge-cut grinding operation or a manual adjustment or traverse is operative for a shoulder grinding operation. It will be readily apparent from the foregoing disclosure that the locking device and the clutch actuating mechanism are interlocked so that the clutches cannot be engaged when the locking device is operative and similarly the locking device cannot be actuated to lock the spindle when either of the clutches 40 are operative.

The operation of this improved wheel spindle positioning and reciprocating mechanism will be readily apparent from the foregoing disclosure.

- 45 Depending upon the grinding operation to be performed, the wheel spindle 15 is either locked against endwise movement to provide a solid end thrust where any axial movement or adjustment of the spindle 15 is desired or the lever 70 may be positioned to facilitate a manual adjustment 50 of the spindle 15 during a shoulder grinding operation, or the lever 70 may be positioned to provide a continuous reciprocating movement of the wheel spindle 15 within the spindle bearings 16 and 17 during a plunge-cut grinding operation. 55 As above described by actuation of the knob 62, the eccentrics 38 and 61 may be relatively adjusted to vary the length of reciprocatory stroke of the spindle 15, as desired.

- 60 It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinabove set forth or shown in the accompanying drawings is to be interpreted as illustrative and not in a limiting sense.

70 I claim:

1. In a grinding machine having a transversely movable slide, a rotatable spindle thereon to support a grinding wheel, bearings in said slide to 75 support said spindle for a rotary and axial re-

ciprocating movement, means including an eccentric mechanism to move said spindle axially, means including a clutch to rotate said eccentric continuously so as to reciprocate said spindle axially within its bearings for a plunge-cut grinding operation, means including a clutch manually to rotate said eccentric so as to move said spindle axially to position said grinding wheel for a shoulder-grinding operation, means including a lever for actuating either one or the other of said clutches which is arranged in a neutral position to maintain both of said clutches disengaged, and a positive locking device positively to lock said spindle against axial movement.

2. In a grinding machine having a transversely movable slide, a rotatable spindle thereon to support a grinding wheel, bearings in said slide to support said spindle for a rotary and axial reciprocating movement, means including a rotatable eccentric to move said spindle axially, means including a clutch to rotate said eccentric continuously so as to reciprocate said spindle axially within its bearings through an adjustable stroke for a plunge-cut grinding operation, manually operable means including a clutch to actuate said eccentric so as to move said spindle axially to position said grinding wheel for a shoulder-grinding operation, a manually operable clutch actuating lever for actuating either one or the other of said clutches which is arranged in a neutral position to maintain both of said clutches disengaged, and a positive locking device positively to lock said spindle against axial movement.

3. In a grinding machine having a transversely movable wheel slide, a rotatable spindle to support said grinding wheel, bearings in said slide to support said spindle for a rotary and axial reciprocating movement, means including an eccentric to move said spindle axially, means including a clutch to rotate said eccentric so as to reciprocate said spindle axially within its bearings through an adjustable stroke for a plunge-cut grinding operation, means including a clutch to actuate said eccentric manually to move said spindle axially to position said grinding wheel for a shoulder-grinding operation, means including an actuating lever for actuating either one or the other of said clutches which is arranged in a neutral position to maintain both of said clutches disengaged, a positive locking device positively to lock said spindle against axial movement, and an interlock between said clutch actuating lever and said locking device to prevent engagement of either of said clutches when said spindle is locked.

4. In a grinding machine having a transversely movable wheel slide, a rotatable spindle to support said grinding wheel, bearings in said slide to support said spindle for a rotary and axial reciprocating movement, means including an eccentric mechanism to move said spindle axially, means including a clutch to rotate said eccentric so as to reciprocate said spindle axially within its bearings through an adjustable stroke for a plunge-cut grinding operation, manually operable means including a clutch to actuate said eccentric manually to move said spindle axially to position said grinding wheel for a shoulder-grinding operation, a manually operable clutch actuating lever for actuating either one or the other of said clutches which is arranged in a neutral position to maintain both of said clutches disengaged, a manually operable positive locking device positively to lock said spindle against axial movement.

5. In a grinding machine having a transversely movable wheel slide, a rotatable spindle thereon to support a grinding wheel, bearings in said slide to support said spindle for a rotary and axial reciprocating movement, means including a rotatable adjustable eccentric mechanism to move said spindle axially, means including a clutch to rotate said eccentric continuously so as to reciprocate said spindle axially within its bearings through an adjustable stroke for a plunge-cut grinding operation, manually operable means including a clutch to actuate said eccentric mechanism to move said spindle axially to position said grinding wheel for a shoulder grinding operation, a manually operable clutch actuating lever for actuating either one or the other of said clutches which is arranged in a neutral position to maintain both of said clutches disengaged, a manually operable positive locking device positively to lock said spindle against an axial movement, and an interlock between said clutch actuating lever and said locking device to prevent actuation of said locking device when either of said clutches are engaged.

6. In a grinding machine having a transversely movable wheel slide, a rotatable spindle to support a grinding wheel, bearings in said slide to support said spindle for a rotary and axial reciprocating movement, means including an adjustable eccentric mechanism to move said spindle axially, means including a clutch to rotate said eccentric continuously to reciprocate said spindle axially within its bearings through an adjustable stroke for a plunge-cut grinding operation, manually operable means including a clutch to actuate said eccentric manually to move said spindle axially to position said grinding wheel for a shoulder grinding operation, a manually operable clutch actuating lever for actuating either one or the other of said clutches which is arranged in a neutral position to maintain both of said clutches disengaged, a manually operable positive locking device positively to lock said spindle against axial movement, and an interlock automatically to lock said clutch actuating lever in a neutral position when said spindle is locked against endwise movement.

7. In a grinding machine having a transversely movable wheel slide, a rotatable spindle on said slide to support a grinding wheel, bearings in said slide to support said spindle for a rotary and axial reciprocating movement, means including an adjustable eccentric mechanism to move said spindle axially, means including a clutch to rotate said eccentric continuously to reciprocate said spindle axially within its bearings through an adjustable stroke for a plunge-cut grinding operation, manually operable means including a clutch to rotate said eccentric so as to move said spindle axially to position said grinding wheel for a shoulder grinding operation, a manually operable clutch actuating lever for actuating either one or the other of said clutches which is arranged in a neutral position to maintain both of said clutches disengaged, a manually operable positive locking device positively to lock said spindle against axial movement, and an interlock automatically to lock said locking device out of engagement when either of said clutches are engaged.

8. In a grinding machine having a transversely

movable wheel slide, a rotatable spindle on said slide to support a grinding wheel, bearings in said slide to support said spindle for a rotary and axial movement, means including a pivotally mounted yoked member to move said spindle axially within its bearings, means including an adjustable eccentric mechanism to oscillate said yoked member, manually operable means including a clutch to rotate said eccentric precisely to position said spindle and grinding wheel for a shoulder grinding operation, power actuated means including a clutch positively to rotate said eccentric to reciprocate said spindle axially within its bearings during a plunge-cut grinding operation, a manually operable clutch mechanism to actuate said clutches so as to render operative either the manually operable means or said power operated means, a manually operable positive locking device to lock said yoked member against oscillation, and an interlock to lock said locking device out of engagement when either of said clutches are engaged.

9. In a grinding machine having a transversely movable wheel slide, a rotatable spindle on said

slide to support a grinding wheel, bearings in said slide to support said spindle for a rotary and axial movement, means including a pivotally mounted yoked member to move said spindle axially within its bearings, means including an adjustable eccentric mechanism to oscillate said yoked member, means to adjust said eccentric mechanism so as to vary the length of the reciprocatory stroke of said spindle, manually operable means including a clutch to rotate said eccentric precisely to position said spindle and grinding wheel for a shoulder grinding operation, power actuated means including a clutch positively to rotate said eccentric to reciprocate said spindle axially within its bearings during a plunge-cut grinding operation, a manually operable clutch mechanism to actuate said clutches so as to render operative either the manually operable means or said power operated means, a manually operable positive locking device to lock said yoked member against oscillation, and an interlock to lock said locking device out of engagement when either of said clutches are engaged.

LENNART A. KASPARSON.
